UNITED STATES PATENT OFFICE.

JOHANNES FISCHBACH AND LUDWIG HENSS, OF WIESBADEN, GERMANY.

PENHOLDER.

SPECIFICATION forming part of Letters Patent No. 627,776, dated June 27, 1899.

Application filed August 22, 1898. Serial No. 689,235. (No model.)

To all whom it may concern:

Be it known that we, JOHANNES FISCHBACH and LUDWIG HENSS, citizens of the Empire of Germany, residing at Wiesbaden, Germany, 5 have invented certain new and useful Improvements in Penholders, of which the following is a specification.

The present invention relates to penholders, and has more particular reference to a 10 device allowing the pen to be readily and easily placed and drawn out, at the same time securing the position of the pen for writing, as more fully described and claimed hereinafter.

15 The accompanying drawings show a construction embodying the invention, in which drawings—

Figure 1 shows an elevation of the penholder, and Fig. 2 is a plan view of same.

20 The penholder is composed of a plurality of wires *a*, placed around a small stem *b* in wood, hardened rubber, or metal. These wires may be substituted by a metal socket slit over a certain portion of its length, so as 25 to present at this end a plurality of resilient strips. The stem *b* is secured in a hole made in the holder *d*. The wires or the above-mentioned socket are supported by an annular shoulder formed by the holder *d* and the 30 stem *b*, which is introduced into said holder. Finally, a covering in rubber or any other elastic substance surrounds the said wires or socket, so as to form an elastic sheath.

The pen is fixed into the end of the holder between the center stem *b* and the cylinder 35 formed by the wires or the slit socket, which can substitute them. The pen is very easily fixed to or removed from the penholder owing to the elasticity of the covering *C*, and this elasticity also keeps the pen fixed for writing. 40 Pens of all dimensions can be used with the above-described arrangement.

Having fully described our invention, what we claim, and desire to secure by Letters Patent, is—

1. A penholder composed of a stem, a plurality of metal wires arranged longitudinally around the end of the stem, and an elastic socket surrounding said wires, substantially as described.

2. A penholder composed of a handle having a socket therein, a stem fitting said socket and projecting therefrom, a plurality of wires surrounding said stem and forming a cylinder thereby and an elastic covering for said 55 wires, substantially as set forth.

In testimony whereof we have hereunto subscribed our names in presence of two witnesses.

JOHANNES FISCHBACH.
LUDWIG HENSS.
